(57) **CLAIM**

The ornamental design for a display screen or portion thereof having a graphical user interface for option selection, as shown and described.

DESCRIPTION

The patent or application file contains at least one drawing executed in color. Copies of this patent or patent application publication with color drawings will be provided by the Office upon request and payment of the necessary fee.

FIG. 1 is a front view of a first embodiment of a display screen or portion thereof having a graphical user interface for option selection showing my new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of an eighth embodiment thereof;

FIG. 9 is a front view of a ninth embodiment thereof;

FIG. 10 is a front view of a tenth embodiment thereof;

FIG. 11 is a front view of an eleventh embodiment thereof; and,

FIG. 12 is a front view of a twelfth embodiment thereof. The variations presented of the display screen or portion thereof having a graphical user interface for option selection in FIGS. 1-4, 5-8, and 9-12 illustrate a set of images sharing a unifying theme and layout in which certain aspects of the claimed elements are presented in varying combinations.

The outermost broken lines and the broken line showing of rounded shapes illustrate an electronic device and the remaining broken lines illustrate portions of the graphical user interface. None of the broken lines form part of the claimed design.
